INVENTOR.

Dominic Robert Perlongo

UNITED STATES PATENT OFFICE

166,272

ASH TRAY

Dominic R. Perlongo, Chicago, Ill.

Application August 11, 1951, Serial No. 16,234

Term of patent 3½ years

(Cl. D85—2)

To all whom it may concern:

Be it known that I, Dominic R. Perlongo, a citizen of the United States, residing at Chicago, in the county of Cook and State of Illinois, have invented a new, original, and ornamental Design for Ash Tray, of which the following is a specification, reference being had to the accompanying drawing, forming part thereof.

The single figure is a perspective view of an ash tray showing my new design.

I claim:

The ornamental design for an ash tray, as shown.

DOMINIC R. PERLONGO.
